UNITED STATES PATENT OFFICE.

MORRIS HANOWER, OF FORT LEE, NEW JERSEY, ASSIGNOR TO THE EAGLE PENCIL COMPANY, OF NEW YORK, N. Y.

COMPASS ATTACHMENT FOR PENCILS.

SPECIFICATION forming part of Letters Patent No. 376,379, dated January 10, 1888.

Application filed October 25, 1887. Serial No. 253,289. (No model.)

To all whom it may concern:

Be it known that I, MORRIS HANOWER, of Fort Lee, in the State of New Jersey, have invented a new and useful Improvement in 5 Compass Attachments for Pencils, of which the following is a specification, reference being had to the accompanying drawings, in which—

Figure 1 is a view of my improved device 10 with the parts so arranged that the device may be used as a pencil. Fig. 2 is a view of the same with the parts in the position they occupy when used as a pair of compasses or dividers. Fig. 3 is a detached view of the "needle-point." Fig. 4 is a like view of a modified form of needle-point. Fig. 5 is an axial section through the hinge which unites the two tubular sections of the device.

The two tubular sections, which form in one 20 position the handle of the pencil and in another position the legs of the compass, are shown at A B. One of them, A, is to receive the pencil P, and for this purpose is made of a pattern similar to any ordinary or suitable 25 pencil-holder. In the present instance it consists of a longitudinal split sheet-metal tube, which receives and clasps the pencil. The other tube, B, is to receive the needle point. The needle-point (shown in Figs. 1, 2, and 3) 30 is a sheet-metal shell of a size to fit in the tube B, having a tapered outer end terminating in the needle a. At its other end is a block or cylinder, b, of rubber or other erasive material. A convenient way of holding this device in 35 place is to provide it with a laterally-projecting pin or stud, c, which will enter and engage one of the series of notches d, formed in one edge of the longitudinal slit or slot e in tube B. The shell C is inserted in the tube B, 40 the pin passing along through the slot e until it comes opposite the notch with which it is to be engaged, and then by a slight turn of the shell the pin is caused to enter the notch, thus holding the shell in place. The shell C is reversible, so that either its rubber end or its 45 needle end can be exposed, according as the device is to be used as a pencil, Fig. 1, or as a pair of compasses, Fig. 2. In lieu of this device, a needle-point--such as shown in Fig.

4—can be used, consisting of a simple cylindrical wooden stick, D, armed at one end with a needle, and adapted to be inserted and held in the tube B in the same way as the pencil P is in tube A. The stick, like the shell C, is reversible.

The tubes A B are hinged together in such manner that when they are fully unfolded their hinged ends may meet and abut against each other, as seen in Fig. 1, in which position they form in effect a single straight tube, which constitutes the pencil handle. To conveniently effect this result, they are provided at their meeting ends each with a pair of laterally-projecting ears, f f and g g. The ears of one of them—as, for instance, ears g g of the tube B—are between the ears f f of the other, and through them passes the hinge or pivot pin h, which has its ends headed, so as to prevent the lateral spreading of the ears. Surrounding the pin h is the spiral spring i, which is closely compressed between the two inner ears, g g, and consequently by its expansion holds these ears closely and tightly against the outer ears, f f, the ears being of sheet metal and sufficiently flexible to permit of this action. In this simple and effective way a permanent and lasting friction hinge-joint is secured, whereby the tubular sections A B, while they can be moved by hand with relation to each other, will be most securely and firmly maintained in their adjusted position, thus rendering unnecessary the use for the purpose of set-screws or tightening-nuts, which require manipulation at each change in the adjustment of the parts.

It will be noted that the axis h of the hinge is so placed that it lies in the plane of the joint formed by the meeting or abutting ends of the two tubes when they are in the position shown in Fig. 1.

Having described my improvement, what I claim herein as new and of my invention is—

1. The combined compass and pencil consisting of the split pencil-holding tube A and the tube B and the reversible needle-point fitting in the same, said tubes being formed and proportioned and hinged together, in the manner described, so that when they are fully

unfolded their adjoining ends will abut, and the two will form in effect a continuous straight tubular pencil-handle. 2. The combination, with the two sections provided at their adjoining ends each with a pair of flexible ears, of the headed pivot-pin uniting said ears and the coiled spring *i*, surrounding said pivot-pin and compressed longitudinally between the said ears, substan-

tially as and for the purposes hereinbefore set forth.

In testimony whereof I have hereunto set my hand this 22d day of October, 1887.

MORRIS HANOWER.
